UNITED STATES PATENT OFFICE.

JAMES H. COFFMAN, OF COLUMBUS, OHIO, ASSIGNOR TO THE WISCONSIN CHAIR COMPANY, OF PORT WASHINGTON, WISCONSIN.

DESIGN FOR A BENT-WOOD CHAIR-SEAT.

SPECIFICATION forming part of Design No. 29,303, dated September 6, 1898.

Application filed August 10, 1898. Serial No. 688,310. Term of patent 14 years.

To all whom it may concern:

Be it known that I, JAMES H. COFFMAN, a citizen of the United States, residing at Columbus, in the county of Franklin and State of Ohio, have invented and produced a new and original Design for Bent-Wood Chair-Seats; and I do hereby declare the following to be a full, clear, and exact description of the same, reference being had to the accompanying drawings, forming a part thereof.

In the said drawings, Figure 1 is a plan view. Fig. 2 is a central longitudinal vertical section on the line 2 2 of Fig. 1. Fig. 3 is a transverse vertical section on the line 3 3 of Fig. 1, and Fig. 4 is a front elevation of a bent-wood chair-seat embodying my new design.

My design relates to the new and original shape or configuration of the article.

The leading or essential feature consists in the unitary design for a bent-wood chair-seat made the subject of illustration, comprising the peculiar and novel shape of the top or upper portion A thereof, which from the rounded rear end of the seat at a as far forward as the points b c b c is of the same horizontal plane or level all along its rear and side portions, the forward limit of the horizontal plane of the rear portion being determined on a substantially semicircular line between the points d d, Fig. 1, whereby this described outer rear and side horizontal or level portion of the said top A is substantially of D-shaped outline, the inner portion of the top A within said level outline or border being depressed below the plane of said level, as best indicated by the sectional views, Figs. 2 and 3, the greatest depth of depression be-

ing at the rear on the semicircular line e e, rising toward the rear between the semicircular lines d d and e e, and from the said line e e extending upward and forward to the line between the points b b, as best shown in Fig. 2. From said line between b b the forward part of the top A is carried over and down on a semicircular line to a line between the points f f, making a rolled or rounded front to the seat, as best shown in Figs. 2 and 4.

Minor features of this design comprise long shallow inward curves of the sides of the top A from the points g g to the points h h and shorter and deeper outward curves from the points h h to the points i i, from which points to the front lower end of the top A the sides are formed on straight parallel lines, while the described rounded rear end a of the top A is curved all around between the points g g, all as best shown in Fig. 1. Also the lower front edge is formed on straight lines between the points f j f j, while the said lower front edge between the points j j is shown formed on the lines of two ogees meeting at the center k.

Having thus described my invention, what I claim as new, and desire to secure by Letters Patent, is—

The design for a bent-wood chair-seat, as herein shown and described.

In testimony that I claim the foregoing I have hereunto set my hand, at Grand Rapids, in the county of Kent and State of Michigan, in the presence of two witnesses.

JAMES H. COFFMAN.
